UNITED STATES PATENT OFFICE.

ALFRED A. KOHN, OF MONTGOMERY, ALABAMA.

DESIGN FOR A SHOE-HEEL.

SPECIFICATION forming part of Design No. 31,830, dated August 1, 1899.

Application filed March 9, 1899. Serial No. 708,453. Term of patent 14 years.

To all whom it may concern:

Be it known that I, ALFRED A. KOHN, a citizen of the United States, residing in Montgomery, county of Montgomery, State of Alabama, have invented and produced a new and original Design for Shoe-Heels, of which the following is a specification.

My invention relates to a new and original design for shoe-heels; and it consists in the configuration of the heel hereinafter shown and described.

Reference is to be had to the accompanying drawings, forming part of this specification, wherein—

Figure 1 is a perspective view of a shoe-heel embodying my invention, and Fig. 2 is a face view thereof.

The leading feature of my design consists in a shoe-heel having the forward corners of the breast convexly rounded or curved, one

of which corners projects forwardly beyond the other, and a concave depression in the breast between said corners.

In the accompanying drawings the letter A indicates a shoe-heel having the two forward corners B C of the breast convexly rounded or curved and a concave depression D in the breast between the corners B C. The corner B projects forwardly beyond a line passing transversely across the corner C, the breast of the heel thus being substantially in ogee form.

I claim—

The design for a shoe-heel, substantially as shown and described.

ALFRED A. KOHN.
